GESELLSCHAFT, OF BERLIN-KOPENICK, GERMANY

BEETLING MILL WITH CLOSED CASING

Application filed January 5, 1929, Serial No. 330,663, and in Germany January 14, 1928.

My invention relates to a beetling mill of the closed-casing type which is improved in various respects with the objects to increase its efficiency, as well as (and considerably) the degree of fineness of the material ground, and to render it even possible to grind also tough and particularly hard metals to a remarkable degree of fineness.

The usual beetling mills having a casing, the walls of which are partly formed of sieves permit only a moderate disintegration of the material to be ground, as finer sieves are by far too delicate to be useful for the purpose in view; besides, they would become obstructed within a short time.

With a closed mill casing, from which the finest particles of the ground material cannot be removed in an easy manner, these particles form after some time a sort of cushion for the coarser particles so that the disintegrating action exerted upon said latter particles, irrespective of whether this action is effected by the beetling members of the mill, or by said particles impinging upon the wall 25 of the same, or upon one another, is weakened. Still another phenomenon preventing a finer disintegration makes its appearance, viz. after a certain degree of fineness depending upon the kind of the material just being 30 ground, its specific weight, the shape of the particles formed by the grinding, the construction and the rotary speed of the mill, the beats of the beetling members upon the material just being ground become weaker 35 and weaker which is due to the reason that the particles more and more circulate along the wall of the mill. The disintegration taking place after that stage has been reached is very slight, and is due chiefly to the friction 40 of the particles at said wall and to their mutual friction when contacting with one another in their common path.

The greater effect of my improved beetling mill is due to a considerable diminishment, if 45 not complete elimination of, the above-mentioned causes. The first characteristic feature of the invention is this, that the particles of the material just being ground are caused to leave for a certain time the path of the beetling members after they have been acted

on by them; after that time has elapsed the particles return to and into their former path in order to be subjected anew to the action of the beetling members. Thus an accumulation of particles in the path of the beetling members is prevented and the cushion action of the smaller particles considerably reduced. Furthermore, because of the removal of the particles from the path of the beetling members, the circular movement of the particles in the casing, is considerably reduced.

The means for attaining these effects can be of different kind. In the first place, the shape of the mill casing is important. When a beetling member impinges upon a particle of the material just being ground, this particle is smashed, and the minute fragments tend to fly away from one another in different directions if there is nothing in the way.

Now, according to this invention, the mill casing is so shaped that the particles can be deviated laterally away from the circular path of the beetling members, but as it is necessary that they later on return into that path in order to be still further disintegrated, means are provided whereby they are conducted back into the said circular path. Various means can be provided for this purpose; a particularly simple one consists in constricting the lower part of the casing so that, although there is in the upper part of the same sufficient room to allow of the particles escaping the beetling members, no such room is in the constricted lower part of the mill casing, the particles being therefore, subjected to the action of the beetling members in this part.

Another means for guiding the particles out of the path of the beetling members consists in the provision of separate members, for instance guide surfaces; or if the particles are sufficiently fine, currents of air or of a suitable gas may be used as means for the purpose in view.

Enclosing the beetling paths in a casing in which a free space for the purpose stated is provided makes it, furthermore, possible to use, with very great success, a current of air for withdrawing the finished product from the mill, and it, besides, enables the particles

already in the mill casing, to be shifted so as to separate the finer particles from the coarser ones. It is also possible to empty the casing completely even with an air current of moderate strength and even if a substance of high specific weight, for instance a metal, has been ground. Also intermediate stages and, therefore, all advantages can be attained which result in continuous service 10 from running with a completely blown-out casing.

On the other hand, the free space in the casing permits the reception of a larger amount of material at a certain definite performance at the mill shaft, as a part of the material is continually out of reach of the beetling members and returns only gradually into the path thereof. In this way a more uniform turning moment at the shaft, 20 as well as lesser variations of the driving power at varying charging, are attained.

In the practical use of a beetling mill the several actions in it, as developing during the grinding operation are not sharply separated from one another, but in the majority of cases they will overlap one another, for instance, as regards an ordinary beetling mill, in this way that a part of the material just being ground is still being disintegrated 30 by the beetling members, whereas another part performs already the detrimental rotation in the casing. As during this rotation no further disintegration worth mentioning takes place, but a pretty considerable amount 35 of power is necessitated to maintain it, it is obvious that reducing, even obviating, this expenditure of power means a considerable increase of the efficiency of the mill.

Because of the grinding effect to which the particles are subjected while circulating in 40 the casing, also due to their rolling along the wall thereof, and similar causes, the individual grains of certain, in fact, many, substances when having been disintegrated to 45 a pulverulent state are changed in that they are rounded off. This is frequently not only superfluous, but also undesired and even detrimental, in that oftentimes, especially as regards metal powders, a possibly torn and 50 jagged shape of the individual particles is demanded. Also as regards this effect, the present invention answers all requirements.

If the air current mentioned in one of the preceding paragraphs is conducted in a certain practical manner, it can be used to effect, or to further, the deviation of the particles from the path of the beetling members.

The invention can be used in connection 60 with several constructional embodiments of beetling mills, irrespective of whether there is only one shaft or a plurality thereof, and whether all shafts rotate in the same direction or not.

The invention is illustrated diagrammatically and by way of example on the accom-

panying drawing on which Figure 1 is an axial section through a beetling mill designed according to this invention, Figure 2 is a transverse section therethrough, and Figure 3 is a plan of a detail, all as fully described 70 hereinafter.

On the drawing, 1 denotes a rapidly revolving shaft, to the inner end of which are secured beetling members 3 and 4. They are enclosed in a three-part casing, consisting 75 of outer portions 6 and 7 and an intermediate portion 5. The portion 6 is so designed as to form also a bearing for the shaft 1, and is, besides, provided with a branch 10. A similar branch 11 is provided on the portion 7. 80 8 and 9 are chambers in the upper halves of the casing portions 6 and 7. The lower halves thereof converge, however, and join directly the neighbouring rim parts of the intermediate casing portion 5, as shown. It is obvious 85 that the particles present in the chambers 8 and 9 can easily evade the beetling members 3 and 4, and as they are no longer whirled round by these members they sink to the lower half of the casing from where they are conducted back into the path 90 of the said members by the oblique and converging walls. Then the particles are again seized by the beetling members and acted on by them, as intended.

The branches 10 and 11, or one or the other thereof, serve for charging the mill with the material to be ground, and both can be used for conducting a current of discharging air 100 through the mill.

The position of the bearing supporting the shaft 1 carrying the beetling members 3 and 4, relative to the casing, is such that said members extend nearly to the bottom of the mill so that they can grasp practically all 105 particles there present and carry them round with, and act upon, them, as intended.

The lateral deviation of the particles in the upper part of the mill, where there are the large chambers 8 and 9 is furthered by oblique faces forming impinging or abutting faces for the particles. Such faces may be formed, for instance, by the sides of a quadrangular plate 12 (Fig. 3) secured to the top of the casing part 5, as shown in Figs. 1 and 2. It appears from these figures that the plate 12 is turned by 45 degrees with respect to the longitudinal axis of the mill, so that the particles impinging upon the two faces facing the approaching particles are 110 deviated to the chambers 8 and 9, i. e. out of the path of the beetling members.

The grinding operation in the mill can proceed in this way that a certain amount of the material to be ground is introduced into the casing, and is disintegrated therein to the desired degree of fineness, whereafter the particles can be removed from the casing by being blown out by means of a current of air, or are otherwise withdrawn. Charging, the 120 125 130

mill, and removing or withdrawing the product, can be effected, however, also continuously, in that one of the branches 10 and 11 is used for the uninterrupted introduction of the material to be ground, as well as of the air, whereas the other branch is used for withdrawing the mixture of air and pulverulent material.

The particles flying about in the chambers 8 and 9, as well as those present between the beetling members, fill up comparatively large spaces, but their number, in relation to the unit of space, is comparatively small, and it is, therefore, possible to render the effect of the air current particularly great. This is warranted also by the feature that, due to the particular arrangement of the apertures in the bulged-out portions or chambers of the mill casing, the speed of the air streaming into, and out of, said portions or chambers changes gradually. On the other hand, obstructions of the branches 10 and 11 located on the top of the mill are completely prevented. Finer particles are diverted off the path 25 of the beetling members, as has already been stated.

I claim:

1. A beetling mill, comprising in combination a closed casing and beetling members 30 adapted to revolve therein, said casing having on either side of said beetling members a chamber for the particles of the material struck by said beetling members to be diverted thereto out of the path of said beetling 35 members, converging walls in said chamber causing the particles to return into the path of said beetling members, and means provided in the top of said casing for diverting the particles to said chambers.

2. A beetling mill as specified in claim 1, 40 in which said means consists of a part having oblique faces disposed at an angle to the plane of revolution of said beetling members.

In testimony whereof I affix my signature.

ERWIN KRAMER.
